EXPANSIBLE BAND

William C. Johnson, East Providence, R. I.

Application October 4, 1946, Serial No. 701,263

2 Claims. (Cl. 139—423)

1

The present invention relates to the textile art, and has particular reference to the manufacture of expandible bands.

The principal object of the invention is to provide an elastic band construction which will not shift or slip when expanded.

Another object of the invention is to provide an elastic band construction which utilizes longitudinal stretchable elements and transverse binding elements which are locked to the longitudinal stretchable elements and to additional longitudinal interlocking elements.

Another object of the invention is to manufacture an elastic band having rubber warp threads and transverse weft threads of cotton filling, the rubber warp threads and the transverse weft threads being locked together by longitudinally extended woven nylon warp threads.

Still another object is to provide an elastic band construction which is particularly suitable for use in surcingles and girths for race horses.

With the above and other objects and advantageous features in view, the invention consists of a novel arrangement of parts more fully disclosed in the detailed description following, in conjunction with the accompanying drawings illustrating a preferred construction, and more specifically defined in the claims appended hereto.

In the drawings:

Fig. 1 is a perspective view showing an arrangement of several elastic bands forming a surcingle and a girth for mounting a saddle on a race horse;

Fig. 2 is an enlarged detail showing the appearance of the face portion of an unstretched band used in forming the surcingle and the girth shown in Fig. 1;

Figs. 3, 4, 5 and 6 diagrammatically illustrate how the successive sheds are formed to effect the weaving of the band;

Fig. 7 is an enlarged view showing, as an illustrative section, the interlocking engagement of the face warp threads with filling thread and an interposed rubber thread;

Fig. 8 is a similar view showing the interlocking engagement of the back warp threads with the filling thread and an interposed rubber thread; and

Fig. 9 is another similar view, being a composite of Figs. 7 and 8, showing the interlocking arrangement of the various threads.

It has been found desirable to provide an elastic band construction which will stretch longitudinally, but not laterally, and which will not slip or shift when it is in stretched condition.

2

Such a construction is particularly suitable for surcingles and girths for mounting saddles on race horses, to prevent movement or slipping of the saddles during a race, but such construction may be used for any elastic band, such as for example abdominal bands, trusses and the like, where it is desired to have a firm securing hold without slipping or shifting.

Referring to the drawings, which illustrate a construction particularly designed for surcingles girths for mounting saddles on race horses, the preferred construction utilizes an upper elastic surcingle 10 which is made of two parallel elastic bands 11, 12 joined at their ends, and having a leather end strap connection 13 and an end buckle connection 14, and a lower elastic girth 15 which preferably is made of three parallel elastic bands 16, 17, 18 secured at their ends to leather end buckle connections 19, 20. The bands 11, 12, 16, 17 and 18 are all of similar construction.

The construction of the elastic band utilizes a plurality of longitudinal rubber warp threads 21, a cotton weft or filling thread 22 and two sets of warp threads, preferably of nylon, which together with the filling thread form a fabric portion on one side of the rubber threads and a fabric back portion on the other side of the rubber threads.

It is a feature of the invention that only a single filling thread is used to effect the weaving of both the face and back portions on opposite sides of the elastic warp threads.

Looking first at Fig. 7, the sets of inelastic warp threads 23a and 23b are shown in their respective positions to illustrate how these threads primarily form the face portion of the band while nevertheless becoming a part of the back portion. For purposes of illustration, the filling thread 22 is shown in two elevations with a rubber warp thread 21 horizontal. It is to be understood, however, that the shuttle containing the filling thread picks across the loom at one elevation and that all the warp threads are selectively shifted vertically to form suitable sheds (see Figs. 3 to 6), for the traverse of the shuttle and filling thread.

As indicated in Figs. 3 to 6, the rubber thread 21 is shifted for each pick (a, b, c and d) of the filling thread, the latter thus passing successively on one side and then the other of the filling thread 22. The face warp threads 23a remain above the filling thread for three picks (a, b and c) and then are under the filling thread for a single pick (d). Likewise other face warp threads 23b remain above the filling thread for three picks (a, c and d) and are below it during one

pick (b). The times when the two sets of face warp threads are below the filling thread are staggered and thus the weave diagrammatically shown in Fig. 8 is attained. Note that each set of face warp threads 23a and 23b are over the filling thread for three picks and then under for the next pick, and since the underpasses are in staggered relation one set or the other of the face warp threads pass under the filling thread on each pick.

Fig. 8 indicates the manner in which the inelastic back warp threads 23c and 23d primarily form the back portion of the band while also becoming a part of the face portion. These back warp threads pass over the filling thread for one pick and then under the filling for three picks. Here again the relation is staggered so that one or the other of these sets of warp threads 23c, 23d pass over each second pick of the filling thread. With reference to Figs 3 to 6, the set of back warp threads 23c are above the filling thread during pick a and below during the other picks b, c and d. The other set of back warp threads 23d are above the filling thread during pick c and below it during the other picks a, b and d.

Fig. 9 is a composite showing of Figs. 7 and 8. On the pick a of the filling thread 22, the sets of face warp threads 23a and 23b, and the set of back warp threads 23c are all above the filling thread, with the rubber threads 21 and the set of back warp threads 23d below the filling thread. On the pick b the face warp threads 23a and the rubber threads are above the filling thread while the face warp threads 23b, and the back warp threads 23c and 23d are below it. On the next pick c the face warp threads 23a and 23b and the back warp threads 23d are all above the filling thread and the rubber threads 21 and the back warp threads 23c are below. On the next pick d of the filling thread, the face warp threads 23b and the rubber threads 21 are above the filling thread while the face warp threads 23a and back warp threads 23c and 23d are all below the filling thread.

At the edge of the band the filling thread 22 is 45 looped around the edge of the band as indicated in Fig. 2.

The expansive band is thus composed of elastic warp threads, inelastic face warp threads, inelastic back warp threads and inelastic weft thread interwoven with all of said warp threads, the repeat for the face warp threads being three up and one down and the repeat for the back warp threads being three down and one up.

The above described construction thus forms a unique weave at both the face and back portions of the band and by choosing a greater or less number of warp threads in a group, any desired pattern of weave may be obtained, keeping in mind the desired interlocking of the various threads together so that there is a firm grip on

the hide of the race horse and a complete elimination of slipping and shifting.

This type of construction is also particularly suitable for abdominal bands, truss bands, and other surgical arrangements, where it is desired to firmly grip part of the human body under tension, with no slippage despite changes in tension produced by movement of the body parts.

While I have described a specific embodiment of the invention, it is obvious that changes in the size, shape and material of the parts may be made to suit the requirements for different expandable bands, without departing from the spirit and the scope of the invention as defined in the appended claims.

I claim:

1. An expansive band composed of elastic warp threads, inelastic face warp threads, inelastic back warp threads and inelastic weft thread interwoven with all of said warp threads, the repeat for the face warp threads being three up and one down and the repeat for the back warp threads being three down and one up.
2. An elastic band construction for surcingles, girths and the like, comprising at least two expandable bands secured together at their ends, each band being composed of elastic warp threads, inelastic face warp threads, inelastic back warp threads and inelastic weft thread interwoven with all of said warp threads, the repeat for the face warp threads being three up and one down and the repeat for the back warp threads being three down and one up.
